UNITED STATES PATENT OFFICE.

EDWARD H. BELDEN, OF FORT WAYNE, INDIANA.

DESIGN FOR AN ELECTRIC-ARC-LAMP CASING.

SPECIFICATION forming part of Design No. 33,430, dated October 23, 1900.

Application filed August 13, 1900. Serial No. 26,799. Term of patent 14 years.

To all whom it may concern:

Be it known that I, EDWARD H. BELDEN, a citizen of the United States, residing at Fort Wayne, in the county of Allen, in the State 5 of Indiana, have invented and produced a new and original Design for Electric-Arc-Lamp Casings; and I do hereby declare that the following is a full, clear, and exact description of the invention, which will enable others skilled in the art to which it appertains to make and use the same, reference being had to the accompanying drawings, which form part of this specification.

My present invention relates to new and 5 original designs for electric-arc-lamp casings.

In the accompanying drawings, Figure 1 is a view in elevation of a cylindrical arc-lamp casing, showing my new design. Fig. 2 is a vertical central section of Fig. 1.

As shown in the said drawings, the leading, distinguishing, or material feature of my design resides in the general contour of the casing, which is cylindrical in form, flaring at both top and bottom, and has its outer surface provided with a series of longitudinal flutes, channels, or grooves in parallel arrangement, as shown, intersected by two annular ribs or convex horizontal bands, also in parallel arrangement.

The casing 1, which exhibits my new design, is cylindrical with gradually-enlarged upper and lower portions. The outer face of the said casing is provided with a series of parallel longitudinal grooves or flutes 4, which are intersected by the encircling convex bands 35 or ribs 5, having upon each side thereof a narrow band 6 of the plain cylindrical surface. The top of the case has an annular ledge, head, or cornice 7, and its contour is a parallel arrangement of three plain convex encircling 40 bands capped by an upright integral lug, from which the lamp is suspended. The bottom of the said case is provided with a plain convex encircling band 8, which is separated from the adjacent flutes 4 by a narrow band 9 of 45 plain cylindrical surface.

Having thus described my invention, what I claim as new, and desire to secure by Letters Patent, is—

The design for an electric-arc-lamp casing, 50 as herein shown and described.

Signed by me at Fort Wayne, Allen county, State of Indiana, this 10th day of August, A. D. 1900.

EDWARD H. BELDEN.
